US00D857010S

(12) **United States Design Patent** (10) Patent No.: **US D857,010 S**
Choi et al. (45) Date of Patent: **** Aug. 20, 2019**

(54) **PORTABLE ELECTRONIC DEVICE**

(71) Applicant: **Samsung Electronics Co., Ltd.**, Suwon-si (KR)

(72) Inventors: **Kwangha Choi**, Seoul (KR); **Sanhui Oh**, Seoul (KR); **Yongseok Bang**, Yongin-si (KR); **Jaehyung Hong**, Seoul (KR)

(73) Assignee: **SAMSUNG ELECTRONICS CO., LTD.**, Suwon-si (KR)

(**) Term: **15 Years**

(21) Appl. No.: **29/645,208**

(22) Filed: **Apr. 24, 2018**

Related U.S. Application Data

(63) Continuation of application No. 29/582,577, filed on Oct. 28, 2016, now Pat. No. Des. 817,952.

(30) **Foreign Application Priority Data**

Jul. 18, 2016 (KR) 30-2016-0034890

(57) **CLAIM**

The ornamental design for a portable electronic device, as shown and described.

DESCRIPTION

FIG. 1 is a front perspective view of a portable electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The broken lines in the drawings depict portions of the portable electronic device that form no part of the claimed design.

1 Claim, 8 Drawing Sheets
